UNITED STATES PATENT OFFICE.

LAYMAN W. BAILEY, OF PRINCETON, WEST VIRGINIA.

RAIL-JOINT.

1,348,075.

Specification of Letters Patent. Patented July 27, 1920.

Application filed November 17, 1919. Serial No. 388,426.

To all whom it may concern:

Be it known that I, LAYMAN W. BAILEY, a citizen of the United States, residing at Princeton, in the county of Mercer and State 5 of West Virginia, have invented certain new and useful Improvements in Rail-Joints, of which the following is a specification.

This invention relates to new and useful Improvements in rail joint chairs and the 10 main object of the invention is the provision of a joint chair formed in two interlocking sections adapted for application to the meeting ends of two rails and provided with simple and efficient means to securely 15 lock said rails against lateral or longitudinal movement.

The invention comprehends a combined joint and chair comprising separable members having provision for their interlocking 20 at the base, whereby a flat uninterrupted bottom bearing surface or base is secured.

A further object of the invention is the provision of a rail joint chair which will possess advantages in points of efficiency 25 and durability, is inexpensive to manufacture and at the same time simple in construction and operation.

Another object is to provide a simple and efficient device for preventing knocking of 30 the rail ends and which will also operate as a bolt lock.

With the foregoing and other objects in view, which will appear as the description proceeds, the invention resides in the combination and arrangement of parts and in the details of construction hereinafter described and claimed, it being understood that changes in the precise embodiment of 35 the invention herein disclosed may be made 40 within the scope of what is claimed without departing from the spirit of the invention.

In the accompanying drawings:—

Figure 1 represents the side elevation of 45 a pair of rail ends connected by this improved joint chair.

Fig. 2 is a top plan view thereof partly in horizontal section.

Fig. 3 is a detail vertical section taken on the line 3—3 of Fig. 2; and

Fig. 4 is a transverse vertical section taken on the line 4—4 of Fig. 2.

In the embodiment illustrated the device constituting this invention is shown applied to two rail ends, 1 and 2, equipped 55 with the ordinary bolt holes 3 to receive the connecting bolts 4.

The chair constituting this invention comprises two interlocking sections 5 and 6. The section 6 which is the outer member of the chair includes a bar or body 7 adapted to fit between the lower face of the tread of the rails 1 and 2 and the base of said rails. This body 7 has a laterally extending flange 8 adapted to fit over the rail base flange and which carries at its lower edge a 60 pair of laterally and inwardly extending longitudinally spaced base plates 9 and 10 which are adapted to extend under the rail base and project at their free edges beyond said base as is shown clearly in Fig. 2. 65

The projecting side edges of these plates 70 9 and 10 are preferably beveled and notched to receive fastening spikes 25. The inner edges of the base plates 9 and 10 diverge toward their free side edges and are beveled 75 downwardly and outwardly as shown at 11.

The chair base plates 9 and 10 carry at 80 their outer edges laterally extending brace supporting plates 12 on which are mounted the braces 13 which are preferably made integral with said plates. These braces 13 connect the plates 12 with the body portion 7 and flange 8 of section 6 and operate to prevent the joint from turning when used on a curve or from buckling when used on 85 a straight track.

The inner face of the body member 7 of section 6 is grooved longitudinally as shown at 14 and is designed to receive between the connecting bolts 4 which pass through apertures 7^a in the body 7 a bowed flat spring 15 which has notches in its opposed ends to fit around the bolts 4. This spring 15 fits between these bolts and prevents knocking of the rail ends, the bowed portion causing the 90 ends of the spring to snugly engage the bolts. As will be seen in Fig. 2, the bowed portion of this spring 15 engages the meeting ends of the rails 1 and 2 and is held 95 yieldably engaged therewith by the bolts 4. The upper walls of the bolt holes 7^a are inclined downwardly from the outer to the inner faces of member 7 so that when the bolts are inserted they strike inclined or sloping walls thereby drawing the rail 100 joint up against the rail. The upper walls of the bolt holes 7^a are inclined downwardly from the outer to the inner faces of member 7 so that when the bolts are inserted they strike inclined or sloping walls thereby drawing the rail 105 joint up against the rail.

The section 5 which is designed to be placed inside the rail ends to be connected, includes a body member 17 similar to the member 7 of section 6, which member is apertured to receive the bolts 4 when the device is to be assembled. A rail base en-

gaging flange 18 extends laterally from the lower edge of said body member 17 and carries midway its ends a base plate 19 which is shaped to fit between the inner ends of 5 the plates 9 and 10 of the other section, the opposed ends of said plate 19 converging toward its free side edge and being beveled downwardly and inwardly to fit on the oppositely beveled ends of the plates 9 and 10. 10 It will be noted that these co-operating plates 9, 10 and 19 extend completely across the chair and opposite sides of the rail base flanges which the chair connects and that the bottom surface of the key or tongue 15 formed by plate 19 is flush with the bottom surfaces of the plates 9 and 10. By this arrangement it will be seen that the bottom surface of the chair has a flat uninterrupted bearing surface throughout its extent, and the 20 relatively wide space covered by the plates 9 and 10 and the key 19 avoids the tendency of the sections 5 and 6 to break down at their meeting ends beneath the vertical axis of the rail section, it being seen that the wide key or tongue 19 is disposed directly below the meeting ends of the rails 1 and 2.

It will thus be seen from inspection of Fig. 1 that the key or plate 19 carried by the inside member 5 slides under the flange 30 8 of the section 6, so that when the outside member 6 is spiked down to the ties T it clamps the inside member 5, thus avoiding the necessity of any spike holes being formed in the member 5.

From the foregoing description, taken in connection with the accompanying drawings, the advantages of the construction and of the method of operation will be readily apparent to those skilled in the art to which 35 the invention appertains and while I have described the principle of operation of the invention together with the device which I now consider to be the best embodiment thereof, I desire to have it understood that 40 the device is merely illustrative and that such changes may be made as are within the scope of the claimed invention.

Having thus described the invention, what

is claimed as new and desired to be secured by Letters Patent, is:—

50

1. A rail joint of the class described including interlocking sections, one section having a body with a base formed of two spaced base plates with their opposed ends beveled and diverging toward their free side edges, the other section comprising a body with a base plate shaped and positioned to fit between the ends of the base plates of the other section with its free end adapted to project under the body of the first mentioned section, whereby a dovetail connection is formed between the sections and spike receiving members carried by the first mentioned section.

55

2. A combined rail joint and chair comprising two oppositely disposed rail engaging members having base portions, one of said base portions comprising longitudinally spaced plates with their inner ends diverging toward their free side edges and beveled 60 downwardly and outwardly, the other base portion being in the form of a plate shaped to fit between the plates of the first mentioned base portion the ends of said plate converging toward its free side edge and 65 beveled downwardly and inwardly.

70

3. A rail joint of the class described including interlocking sections each having a rail web engaging member, said members being provided with registering bolt holes, 75 a seat in the inner face of one member between said holes, and a bowed flat spring positioned in said seat and having notched 80 ends, bolts passing through said holes and notches, said sections having laterally extending base portions carried by the lower edges of the web engaging members thereof and shaped to interlockingly connect when 85 assembled, and spike receiving means carried by the other said section.

90

In testimony whereof I affix my signature in presence of two witnesses.

LAYMAN W. BAILEY.
